UNITED STATES PATENT OFFICE.

FRANCESCO FEDIRICE AND NATALE POLLI, OF CHICAGO, ILLINOIS.

SHOE.

1,294,075.

Specification of Letters Patent.

Patented Feb. 11, 1919.

Application filed August 23, 1918. Serial No. 251,168.

To all whom it may concern:

Be it known that we, FRANCESCO FEDIRICE and NATALE POLLI, a subject of the King of Italy and a citizen of the United States, 5 respectively, residing at Chicago, in the county of Cook and State of Illinois, have invented new and useful Improvements in Shoes, of which the following is a specification.

10 This invention relates to new and useful improvements in shoes and the principal object of the invention is to provide simple means for fastening one part of the upper to the other to secure the shoe on the foot.

15 Another object of the invention is to provide a device of this character which is simple and durable in construction, reliable and efficient in operation and one which can be manufactured and placed upon the market at a minimum cost.

20 The invention also consists in certain other features of construction and in the combination and arrangement of the several parts, to be hereinafter fully described, illustrated in 25 the accompanying drawings and specifically pointed out in the appended claim.

25 In describing our invention in detail, reference will be had to the accompanying drawings wherein like characters denote like 30 or corresponding parts throughout the several views, and in which:—

Figure 1 is a view with the flap in closed position, parts being broken away.

Fig. 2 shows the flap in open position.

35 Fig. 3 is a sectional detail view showing the arrangement of one of the fasteners.

In these views 1 indicates the shoe having its upper 2 provided with a front opening, as usual. To one side of the upper adjacent 40 this opening we place a row of male members 3 of the well known type of snap

fasteners shown in the drawing. The other edge of the upper has secured thereto or formed therewith a flap 4 which carries the female members 5 of the fasteners. We 45 make this flap in the form of a fly. This flap is formed of the upper part 6 and the under part 7 which are suitably stitched together excepting at their outer edges, though at this point about centrally thereof said 50 front edges are stitched together for a short distance as at 8. The under flap carries the female members.

It will thus be seen that the two members of the fasteners may be easily and quickly 55 placed together to hold the shoe closed. It will also be seen that the fasteners are entirely covered by the upper flap so that they are hidden from view and protected from the elements. A shoe provided with 60 our invention may be quickly and easily put on and taken off and the fly arrangement of the flap facilitates these actions.

It is thought from the foregoing description that the advantages and novel features 65 of our invention will be readily apparent.

We desire it to be understood that we may make changes in the construction and in the combination and arrangement of the several parts, provided that such changes 70 fall within the scope of the appended claim.

What we claim is:

A shoe having an opening therein, a flap having upper and lower parts with their outer edges free of each other and snap devices having a part carried by the under flap and a part carried by the upper adjacent the opening for holding the flap closed. 75

In testimony whereof we affix our signatures.

FRANCESCO FEDIRICE.
NATALE POLLI.
